(57) **CLAIM**

The ornamental design for a ladder hook sleeve, as shown and described.

DESCRIPTION

FIG. 1 is a front perspective view of a ladder hook sleeve, showing our new design;

FIG. 2 is a front elevation view thereof;

FIG. 3 is a rear elevation view thereof;

FIG. 4 is a right-side view thereof;

FIG. 5 is a left side view thereof;

FIG. 6 is a top plan view thereof; and,

FIG. 7 is a bottom plan view thereof.

The broken line showing of a ladder rail hook depicts environment and forms no part of the claimed design.
